Primary Examiner — Thomas Johannes*Assistant Examiner* — Melvin Davis(74) Attorney, Agent, or Firm — Christine M. Cooper(57) CLAIM

The ornamental design for a music themed frame, as shown and described.

DESCRIPTION

FIG. 1 is a front perspective view of a music themed frame showing my new design;

FIG. 2 is a front elevational view thereof, wherein the protruding internal detail on the right inner wall of the music themed frame is a broken line and is not part of the claimed design;

FIG. 3 is a rear elevational view thereof, wherein the rear innermost surface inside the broken line is not part of the claimed design;

FIG. 4 is a right side elevational view thereof;

FIG. 5 is a left side elevational view thereof;

FIG. 6 is a top plan view thereof; and,

FIG. 7 is a bottom plan view thereof, wherein the broken line on the lower edge is not part of the claimed design.
